UNITED STATES PATENT OFFICE.

ABRAHAM LERNER, OF BROOKLYN, NEW YORK.

COMBINED TIE AND FASTENER.

1,426,883.

Specification of Letters Patent. Patented Aug. 22, 1922.

Application filed February 9, 1921. Serial No. 443,626.

To all whom it may concern:

Be it known that I, ABRAHAM LERNER, a citizen of the United States, and a resident of the city of New York, borough of Brooklyn, in the county of Kings and State of New York, have invented a new and Improved Combined Tie and Fastener, of which the following is a full, clear, and exact description.

10 This invention relates to wearing apparel and particularly to an improved form of tie and fastener and has for an object to provide a construction wherein the tie may be held in proper place by a collar button without 15 danger of the tie rotating or moving out of correct position.

Another object of the invention is to provide a combined tie and collar button wherein in the tie is provided with a socket having a 20 polygonal opening for receiving a button with a similar formed head and a flat shank whereby the tie is held against rotation while the button acts in the combined capacity of a collar button and a support for the tie.

25 In the accompanying drawing—

Figure 1 is a perspective view of part of a shirt and collar with a tie and fastener embodying the invention shown applied thereto.

30 Figure 2 is a fragmentary sectional view through Figure 1 on line 2—2, the same being on an enlarged scale.

Figure 3 is a top plan view of a fastener or body embodying certain features of the 35 invention.

Figure 4 is a sectional view through Figure 3 on line 4—4.

Figure 5 is a perspective view of the button shown in Figure 3 on an enlarged scale.

40 Figure 6 is a rear view of the necktie shown in Figure 1.

Figure 7 is a transverse sectional view through Figure 5 on line 7—7.

Referring to the accompanying drawing 45 by numerals, 1 indicates a shirt of any desired kind and 2 a collar of any desired kind. The collar 2 is held in place by collar buttons as is usual but instead of providing an ordinary collar button at the front a special 50 button and tie support 3 is provided. This button and tie support or fastener is formed with a base 4; a flat tapering shank 5 and a

head 6. The head 6 is formed with a round portion 7 and a polygonal-shaped portion or section 8 having its sides inclined inwardly 55 toward the round portion and forming therewith a shoulder. The head in the drawing has been shown as a square but it may be formed with more or less sides. The head 6 is adapted to fit into a socket 9 secured in 60 any desired manner to the rear part of the bow 10, said bow being of the usual construction of bow-ties except that it is not provided with a guard but only with the socket 9. This socket is formed with a polygonal opening 11 for receiving the head 6 into which it snaps when the tie is placed in 65 position as shown in Figure 1. When the button 3 is placed in position in the collar and neck band the flat shank 5 prevents the 70 same from turning which also acts to prevent the tie 10 from turning when once placed in position, whereby the tie is correctly held without the use of a guard and, consequently, without having the usual stiff 75 appearance which is found in ties having guards.

What I claim is:

1. A combined tie and fastener comprising a tie having a polygonal socket on its 80 inner face, and a button adapted to pass through the button hole of the neck band of a shirt and the button holes of a collar and snap into the socket of the tie, said button consisting of a base, a flat and tapering 85 shank, the shank being of uniform thickness throughout its length and the portion thereof of which lies in the button hole of the neck band being of a width to prevent it from turning therein, and a polygonal head terminating in a round portion and provided with a polygonal portion having its sides inclined inwardly toward the round portion and forming therewith a shoulder, the polygonal portion of the head fitting snugly in 95 the socket of the tie and preventing the turning of the tie thereon.

2. In a fastener, a button comprising a base, a flat tapering shank, and a head having a round terminal portion, and a polygonal portion having its sides inclined inwardly toward the round portion and forming therewith a shoulder.

ABRAHAM LERNER.
